UNITED STATES PATENT OFFICE.

GEORGE L. VAIL, OF DENVER, COLORADO.

CONDENSER.

1,103,386.

Specification of Letters Patent. Patented July 14, 1914.

Application filed December 12, 1912. Serial No. 736,282.

To all whom it may concern:

Be it known that I, GEORGE L. VAIL, a citizen of the United States, residing at Denver, in the county of Denver and State 5 of Colorado, have invented certain new and useful Improvements in Condensers, of which the following is a specification.

My invention relates to condensers and more particularly to condensers of the class 10 employed for condensing the ammonia gases discharged from the compressor in an artificial ice plant.

The primary object of the present invention is to provide an apparatus of novel construction in which the hot gas delivered from the compressor is, by the use of the least possible quantity of cooling fluid, liquefied in the minimum of time.

Another object of my invention resides 20 in providing a construction by which a continuous passage is maintained for the unobstructed flow of gases between the point of the condenser at which they are delivered from the compressor and the point at which 25 the condensed fluid is discharged, thereby effectively preventing the apparatus from becoming "gas-bound" by obstructive accumulation of liquid, and completely averting any sudden increase in pressure in the condenser in case the supply of cooling fluid 30 is temporarily discontinued.

In the operation of my improved condenser, the cooling fluid is applied exteriorly to a plurality of connected containers 35 through which the gases delivered from the compressor are conducted from one end of the apparatus to the other, and incapacitation of the machine by accumulation of sediment or freezing is thus prevented, 40 while no pump is required to effect a circulatory flow of the water by which the gas is liquefied.

In proceeding in accordance with my invention, I provide a series of consecutively 45 connected containers of large capacity and thus eliminate the employment of a multiplicity of friction inducing fittings and bends which retard the flow of the gaseous and liquid ammonia and in consequence impede the proper operation of the compressor from which the gases are derived, the cost 50 of repairs and the chances of impairment of the machine by clogging or leakage are by the same cause, materially reduced and in-

asmuch as, in comparison with condensers 55 of different construction, the use of my apparatus greatly expedites the condensation of ammonia gases without requiring an increase in the supply of cooling fluid, it follows that it may be made of smaller 60 compass than other condensers of the same capacity and that in consequence it requires less floor space and less strength of supporting structure, while the cost of its installation and operation is proportionately reduced. 65

Having thus explained the objects of my invention and its advantages over other machines in the art as it is at present known to me, I will now proceed to describe its 70 construction and operation by reference to the accompanying drawings in the various views of which like parts are similarly designated, and in which,

Figure 1 represents an end elevation of 75 my improved condenser, partly in section, Fig. 2, a fragmentary horizontal section taken along the line 2—2, Fig. 1, Fig. 3, an enlarged cross-sectional view of one of the containers comprised in the apparatus 80 and the adjacent portion of the structure upon which the same are supported, and Fig. 4, an elevation, partially in section, showing my condenser in combination with the compressor of an artificial ice-plant. 85

Referring more specifically to the drawings, my improved condenser is composed of a plurality of horizontally disposed, cylindrical containers 2 which being arranged in two series A and B are supported in 90 seats 3 formed equidistantly in the convergent edges of two parallel trapezoidal walls 4 made of concrete or other suitable material and provided with archways 5 through which access may be had to the chamber 95 formed between their inner surfaces and beneath the two series of containers.

The units of the two series being of equal length, have their ends disposed in vertical planes adjacent the outer surfaces of the 100 walls and they are held in their respective seats against outward displacement upon brackets 6 which are secured to the walls by means of bolts 7. The stability of the structure may be increased by applying between 105 the two walls 4, one or more tie rods, such as shown at 8 in Fig. 1.

The containers comprised in the two con-

vergently disposed series are hermetically closed at their ends by means of heads 9 which are secured therein by welding, brazing or other suitable method and which are 5 provided with central openings 10 that are countersunk at their outer ends to receive the flanges of return bends 12 by the use of which the several containers of each series are connected for the flow of fluid from one 10 to another.

The containers 13 at the upper ends of the two series are made of larger diameters than those which follow, for the purpose of removing the heat of compression from the 15 gas before it is being condensed by contact with the cooled walls of the containers, and of eliminating all possibility of back pressure and consequent impediment of the proper operation of the compressor from 20 which the gases are delivered to the condenser.

The connection between the compressor 30 and the condenser is as shown in Fig. 4 of the drawings established through the medium of a conduit 14 which by means of a branch-fitting 15 is connected with the openings in the heads at one end of the preliminary units 13 of the two series of containers.

Valves 16 connected in the branch 15 are provided to disconnect either one of the two series from the system and an oil-trap 17 disposed between the said branch and the pipe 14 serves to separate all greasy matter carried by the gas, before the latter enters the condenser.

The units of each series are successively connected by means of the return-bends hereinbefore referred to, to establish a continuous passage for the flow of fluid from the preliminary container 13 at the upper end of the series to the lowermost unit which serves as a receiver for the condensed liquid discharged from the preceding units, and the lowermost units of the two series are by 45 means of valve-controlled pipes 18 connected with the conduit 29 through which the liquid discharged from the condenser is delivered either directly to the freezing plant or to a suitable receptacle.

The cold water which by its cooling effect, is the primary cause of the liquefaction of the gases conducted through the series of containers, is applied exteriorly of the latter by means of slotted pipes 19 which extend longitudinally above the containers and which are provided with bowls 20 through the medium of which the water supplied through a plurality of valve-controlled branch-pipes 21 of a header 22, is introduced into their interiors.

The pipes 19 are supported along their entire extent upon benches 23 which are secured upon the respective containers and 65 whose sides extend divergently for the even

distribution of the water discharged through the slots of the respective pipes, over the exterior surfaces of the containers with which they are associated.

The slots of the pipes 19 extend longitudinally of the same and preferably in their upper portions and the water discharged through the slots, flows over the surfaces of the pipes onto the slanting sides of the benches 23 upon which the latter are supported, and thence across the entire exterior surfaces of the containers whose walls are in consequence continuously cooled for the condensation of the gases brought in contact with the interior surfaces of the same.

In the operation of my improved condenser, the hot gas introduced into the preliminary containers 13 at the upper ends of the two series, expands therein and thus prevents back pressure to the compressor from 80 which it is delivered, while it loses to a considerable degree its heat of compression. A portion of the gases delivered into the primary unit of each series is condensed by contact with the cooled circumferential wall 90 of the same, and falls in the form of liquid ammonia in the lower portion of the container where it accumulates until its level rises above the lower end of the central openings in its heads, when it overflows into the next succeeding unit which, in like manner, is filled to the level of the openings in its head and which in its turn discharges its excess liquid into the subjacent unit. The condensed liquid is in this manner conducted 95 from one unit to the other until it reaches the receivers at the lower end of the series from which it is discharged through the pipes 18 into the conduit 29 which delivers it either directly to the freezing plant or into 100 a suitable receptacle. The uncondensed gases flow from the preliminary unit of the series at a reduced temperature into the next succeeding unit where they come in contact not only with the continuously cooled wall 110 thereof, but also with the body of liquid ammonia contained in the bottom portion of the same, which liquid being of lower temperature than the gases discharged from the preceding unit, aids materially in effecting 115 their speedy condensation. The uncondensed gas is discharged from the second unit into the next succeeding one in which the above described operation is repeated and it is thus conducted through the entire 120 series of units at a continuously reduced temperature until it reaches the lowermost one of the series at a temperature so low that it is entirely converted into liquid by contact with the cooled wall of the same as 125 well as by the cooling effect of the body of ammonia contained in its lower portion.

It will be evident that in the operation of the apparatus the portion of the containers below the openings in their heads are 130

always filled with liquid ammonia, which, as hereinbefore explained, expedites by its cooling influence, the condensation of the gas which flows through the two series and that the upper portions of the containers are continuously maintained in communication with each other for the unobstructed passage of gases in either direction, thus preventing the condenser from becoming gas-bound by obstructive accumulation of liquid.

10 While I have shown and described my invention in the best form at present known to me, I desire it understood that the apparatus is susceptible of variations in the construction and arrangement of its parts without any material departure from the principle and nature of the same.

15 What I claim and desire to secure by Letters-Patent is:

20 1. In a condenser, a series of containers having openings which by their position relative to the bottom surfaces thereof adapt them to retain in their lower portions, a quantity of liquid to a determinate level, connections between said openings to provide a continuous passage for fluid from the container at one end of said series to that at the other end of the same, one of said end-containers being of greater capacity than the others and having an inlet for fluid, and means for subjecting the contents of the containers, to the influence of a cooling fluid.

25 2. In a condenser, an obliquely disposed series of successively arranged containers having openings which by their position relative to the bottom surfaces thereof adapt them to retain in their lower portions, a quantity of liquid to a determinate level, connections between said openings to provide a continuous passage for the flow of fluid from the upper container of the series to the lower one, and means for applying a cooling liquid separately to each of said containers.

30 3. In a condenser, two divergently disposed series of successively arranged containers, having openings which by their position relative to the bottom surfaces thereof adapt them to retain in their lower portions, a quantity of liquid to a determinate level, connections between said openings to provide a continuous passage for the flow of fluid from the uppermost container of each series, to the lowermost one of the same, the uppermost containers of the two series having a connection with a common source of fluid-supply, and means for applying a cooling liquid separately to each of said containers.

35 4. In a condenser, an obliquely disposed series of cylindrical containers arranged successively one above another, and connected for the flow of fluid from the container at the upper end of the series to that at the lower end of the same, and slotted

pipes disposed above said containers, to apply a cooling fluid separately to the exterior surfaces of the same.

5. In a condenser, two divergently disposed series of cylindrical containers arranged successively one above another, and connected for the flow of fluid from the uppermost container of each series, to the lowermost one of the same, means for connecting the said uppermost containers with a common source of fluid-supply, and pipes disposed above said containers to apply a cooling fluid separately to the exterior surfaces thereof.

6. In a condenser, two walls having divergent edges and in said edges, a succession of seats, series of containers supported in corresponding seats of said walls and having in their ends, openings of smaller diameter, connections between said openings to establish a continuous passage for the flow of fluid from the uppermost container of each series, to the lower one of the same, means for connecting the said uppermost containers with a common source of fluid supply, and pipes arranged above said containers to apply a cooling fluid to the exterior surfaces thereof.

7. In a condenser, a series of substantially horizontal conduits connected for the flow of fluid from the conduit at one end of said series to that at the other end of the same, slotted pipes above said conduits, bowls on said pipes in communication with their interiors, and means for supplying a cooling fluid to said bowls.

8. In a condenser, a series of substantially horizontal conduits connected for the flow of fluid from the conduit at one end of said series to that at the other end of the same, slotted pipes above said conduits, and means for distributing a cooling fluid discharged through the slots of said pipes over the surfaces of the respective conduits.

9. In a condenser, a series of substantially horizontal conduits connected for the flow of fluid from the conduit at one end of said series to that at the other end of the same, slotted pipes above said conduits, and benches interposed between said pipes and the respective conduits, for the support of the former, said benches having sloping sides for the distribution of a cooling fluid discharged through the slots of the pipes supported thereon, over the surfaces of the respective conduits.

10. The combination with the compressor of an artificial ice-plant, of a flue providing a continuous passage for the vapors discharged from the compressor, from one of its ends to the other, and means for subjecting the contents of said flue to the influence of a cooling fluid, the said flue including sections of increased diameter in which portions of the liquid to which said

vapors are condensed while passing through the flue, are retained.

11. The combination with the compressor of an artificial ice plant, of a flue providing a continuous passage for the vapors discharged from the compressor, from one of its ends to the other, and means for subjecting the contents of said flue to the influence of a cooling fluid, the said flue comprising sections connected at points above their interior bottom surfaces whereby they

are adapted to retain portions of the liquid to which said vapors are condensed while passing through the flue.

In testimony whereof I have affixed my 15
signature in presence of two witnesses.
